UNITED STATES PATENT OFFICE.

GEORGE RENNINGER, OF GLENSIDE, PENNSYLVANIA, ASSIGNOR TO PHILIP WUNDERLE, OF EDGEHILL, PENNSYLVANIA.

DESIGN FOR A BOX.

SPECIFICATION forming part of Design No. 34,786, dated July 16, 1901.

Application filed May 20, 1901. Serial No. 61,190. Term of patent 3½ years.

To all whom it may concern:

Be it known that I, GEORGE RENNINGER, a citizen of the United States, residing at Glen-side, in the county of Montgomery, State of Pennsylvania, have invented and produced a new and original Design for Boxes, of which the following is a specification, reference being had to the accompanying drawing, forming part thereof.

The leading feature of my design for a box is a body simulating a clock-case and a lid simulating a cornice thereon.

The figure represents a perspective view of a box embodying my design.

In the drawing, A designates the body of the box and B the removable lid thereof, both

being of quadrilateral form. On the front of the body are representations of a dial C, side columns D, and base E. On the front of the lid B is the representation of a cornice, which is composed of representations of horizontally-extending separated beads F.

Having thus described my invention, what I claim as new, and desire to secure by Letters Patent, is—

The design for a box substantially as shown and described.

GEORGE RENNINGER.
